US00D514412S

(12) **United States Design Patent** (10) Patent No.: **US D514,412 S**
 Lawrence et al. (45) Date of Patent: **** Feb. 7, 2006**

(54) **NAILER**

(75) Inventors: **Bobby Lynn Lawrence**, Lawrenceburg, IN (US); **Daniel John Harty**, Mason, OH (US); **Bryan Thomas Humpert**, Cincinnati, OH (US); **Gregory Allen Kramer**, Cincinnati, OH (US)

(73) Assignee: **Campbell Hausfeld/Scott Fetzer Company**, Harrison, OH (US)

(**) Term: **14 Years**

(21) Appl. No.: **29/195,586**

(22) Filed: **Dec. 15, 2003**

(51) LOC (8) Cl. **08-05**

(52) U.S. Cl. **D8/68**

(58) Field of Classification Search .... **D8/14.1, D8/61, 62, 63, 64, 65, 66, 67, 68, 69, 70; 81/57.11, 429, 464, 465, 466, 469, 489; 173/13, 173/169, 178, 213, 217; 227/8, 114, 120, 227/130, 136, 142; 310/50; 408/20, 124, 408/125, 234, 241 R; 451/358**

See application file for complete search history.

(57) **CLAIM**

The ornamental design for a nailer, as shown and described.

DESCRIPTION

FIG. 1 is a perspective view of the nailer of our new design; FIG. 2 is a right side view thereof;

FIG. 3 is a left side view thereof;

FIG. 4 is a top view thereof;

FIG. 5 is a front view thereof;

FIG. 6 is a rear view thereof; and,

FIG. 7 is a bottom view thereof.

The broken line showings of FIGS. 1–7 are for illustration purposes only and form no part of the claimed design.

1 Claim, 5 Drawing Sheets
